UNITED STATES PATENT OFFICE.

WILLIAM C. HEDGCOCK, OF CHICAGO, ILLINOIS, ASSIGNOR TO AMERICAN STEEL FOUNDRIES, OF NEW YORK, N. Y., A CORPORATION OF NEW JERSEY.

DRAFT-YOKE.

1,223,489.

Specification of Letters Patent. Patented Apr. 24, 1917.

Application filed October 25, 1915. Serial No. 57,667.

To all whom it may concern:

Be it known that I, WILLIAM C. HEDGCOCK, a citizen of the United States, residing at Chicago, in the county of Cook and State of Illinois, have invented certain new and useful Improvements in Draft-Yokes, of which the following is a specification.

My invention relates to draft appliances and has particular reference to a novel yoke.

As is well understood it is common to employ a yoke within which the draft rigging springs are confined, the forward end of the yoke being rigidly secured to the coupler shank. Many improvements have been suggested in the means of attachment of the yoke to the shank some of such means presenting many advantages. I have, however, conceived the idea of employing a form of connection which shall be rigid and immovable under all working conditions of the draft rigging but which may be disconnected without destructive effort as to any of the parts of the yoke or attaching means. In the device contemplated by me the removal of a single bolt will permit the separation of the two arms of the yoke and the disconnection of the yoke from the draw bar shank. However, while the bolt is in place and the two arms of the yoke are thus secured together it becomes impossible to remove the yoke from the draw bar.

The invention will be more readily understood by reference to the accompanying drawings, wherein—

Figure 1 is a side elevation of a coupler yoke constructed in accordance with my invention;

Fig. 2 is a plan view thereof with the coupler shank omitted;

Fig. 3 is a section on the line 3—3 of Fig. 1; and

Fig. 4 illustrates a slight modification of the construction shown in the preceding figures.

Referring more particularly to the drawings it will be seen that the coupler shank 10 is provided with the usual enlarged butt end thereby forming undercut shoulders 11. The yoke of my invention comprises upper and lower arms 12, 13 separately formed but united at their ends by means of apertured lugs 14 and a bolt 15. The forward ends of the arms are provided with side flanges 16 located outside of the coupler shank and terminating at their forward ends in a hook

17 which extends across the arm and is in effect a bent down or upset end of the arms 12, 13. Projecting inwardly from each of the arms near the hooked ends thereof are dowels 18, so formed as to register with the holes in the coupler butt. To the rear of the ribs and likewise extending transversely across each of the arms 12, 13 is an abutment 19 with which the end of the coupler shank engages. In Fig. 1 I have shown a follower 20 in place. This follower may assume different forms from that shown.

The yoke is applied as follows: It being assumed that the yoke is in two parts, or halves, each half is applied by inserting the hook portion 17 in the undercut portion 11 of the draw bar shank, it being possible to do this only when the arm or half is in an angular position, that is with the rearward ends of the halves separated materially. After the hooks on the draw bar and yoke are engaged the rearward ends of the halves are brought together, the abutments 19 lying behind the butt of the coupler. When the parts have been brought together and the apertured lugs brought into engagement the bolt 15 is inserted and a nut applied thereto. As long as the yoke arms are in this position it will be seen that the yoke cannot be separated from the draw bar thus providing a secure connection by the use of but a single bolt. There is practically no strain on this bolt due to the fact that the pull on the yoke is in a straight line from the hooks to the rear end thereof.

In Fig. 4 I have shown a slightly modified construction in that the abutments 19 shown in Fig. 1 are omitted. In order to secure the desired result I have constructed the butt end of the coupler in a slightly different manner. In the butt end 21 I have provided a pair of transverse apertures 22 on the top and bottom faces of the butt, these apertures extending in a curved line thereby forming an undercut shoulder 23. The upper and lower arms 24, 25 of the yoke are provided at their forward ends with side webs 26 which lie outside of the butt of the coupler and at the ends the arms are provided with hooks 27 shaped to conform to the shape of the recesses 22. By reason of the shape of the hooks and recesses it is not possible to insert or remove the arms except when their free ends are separated, the action in applying or removing the arms be-

ing the same as that described in connection with the preceding figures.

A construction such as described will be found efficient in service in that it cannot accidentally become detached, the parts may be made heavy and rigid and the possibility of the shearing of rivets is avoided. Obviously modifications may be made in the construction shown and such modifications as are within the scope of my claims I consider within the spirit of my invention.

I claim:

- 15 1. In a draft yoke, the combination of two halves, an inturned hook provided at the forward end of each half, webs at the sides of the members, said webs joining the ends of the hooks to the sides of the arms, and a bolt for uniting the halves at their rearward ends, substantially as described.
- 20 2. In a draft device, the combination of a coupler shank having an enlarged butt end providing undercut shoulders, a yoke composed of two separate parts, the forward ends of said parts being bent in two directions to provide a hook adapted to engage beneath said undercut shoulders, and a bolt
- 25

for uniting said two parts of the yoke, the arrangement being such that the parts of the yoke may not be disengaged from the draw bar shank when united to each other.

3. In a draft device the combination of a coupler shank providing undercut shoulders at its butt end, a two part yoke, each of the two parts of the yoke being provided at one end with a portion which is deflected downwardly and backwardly, a transverse abutment provided on each of said two parts and located between the ends thereof, and a bolt for uniting the two parts of the yoke, the arrangement being such that said parts of the yoke may be operatively attached to the butt end of the coupler only when the opposite ends of the parts are separated.

It witness whereof I have hereunto signed my name in the presence of two subscribing witnesses.

WILLIAM C. HEDGCOCK.
